UNITED STATES PATENT OFFICE.

ROBERT H. READ, OF SCHENECTADY, NEW YORK, ASSIGNOR TO GENERAL ELECTRIC COMPANY, A CORPORATION OF NEW YORK.

ELECTRIC CUT-OUT.

No. 818,291.

Specification of Letters Patent.

Patented April 17, 1906.

Application filed September 26, 1904. Serial No. 226,906.

To all whom it may concern:

Be it known that I, ROBERT H. READ, a citizen of the United States, residing at Schenectady, county of Schenectady, State of New York, have invented certain new and useful Improvements in Electric Cut-Outs, of which the following is a specification.

My invention relates to electric cut-outs of the fuse type; and its object is to provide a novel form of fuse to open electric circuits of high voltage with certainty and without damage to the fuse structure.

In a former patent, No. 716,475, issued to me December 23, 1902, I have described a novel form of switch which is particularly effective in rupturing currents of high potential and which involves the employment of hollow or tubular contacts, through which is driven at the moment of separation a strong blast of air which acts to stretch out within the contacts the arc formed between them, so that the arc is quickly broken.

My present invention consists in providing such a set of contacts placed in an inclosed chamber with the fuse with means responsive to a rise of pressure in the chamber operatively connected to one of the contacts, so that the pressure produced in the chamber by the volatilization of the fuse acts both to produce the separation of the tubular contacts and to cause a blast of air within the tubes upon their separation, so as to break the arc.

Another feature of my invention consists in arranging the fuse as a plug-fuse adapted to be inserted and withdrawn conveniently, with connections within the casing for placing the fuse in series with the tubular contacts when it is inserted in place.

My invention will best be understood by reference to the accompanying drawings, in which—

Figure 1 shows a cross-sectional view of a fuse arranged in accordance with my invention, and Fig. 2 shows a modified form of the same.

In Fig. 1, A represents a cylindrical casing, provided at its ends with the heads *a* and *a'*. The casing is preferably lined with insulating material, as shown. B represents a piston which is movable within the casing and which

is made partly or wholly of insulating material, as indicated. This piston B carries a sleeve *b*, extending through the head *a'*, which forms a guide for the sleeve. Inside 55 the sleeve *b* is carried a conducting-tube C, which is provided at its outer end with a terminal *c*, as shown. The piston B is normally held in the position shown by the spiral compression-spring E. In this position of the piston the conducting-tube C is pressed into engagement with the stationary tube D, which is supported from the opposite head *a* and insulated therefrom, as shown. The tube D is provided with the lug *d*, which 60 forms one terminal for the fuse proper, which, as shown, consists of a strip of fusible metal F, provided at its ends with the terminal contacts *f* and *f'*. These terminal contacts are carried by an insulating-rod I, which for convenience is provided with a handle H, by means of which the fusible strip may be inserted in place and withdrawn for renewal. The contact-terminal *f* engages the lug *d* on the stationary tube D, while the other contact-terminal *f'* engages the terminal G. The tube D has an insulating-covering to prevent an arc springing to it from fuse F. The head *a* is provided with an outlet *a'*, registering with the interior passage of stationary tube D.

The operation is as follows: Normally the current enters at the terminal *c* and passes through the tube C, tube D, lug *d*, fuse-terminal *f*, fuse-strip F, fuse-terminal *f'*, and out 65 at terminal G. Now if an overload occurs on the circuit the fusible strip will be blown and by its volatilization will produce an increase in pressure within the casing A, which will drive piston B backward, compressing 70 spring E and withdrawing the tube C from its engagement with the stationary tube D. A second break will thus be produced in the circuit in series with the fusible strip F, and the pressure within the inclosed chamber, 75 which accumulates until the piston moves, produces a rush of air and hot gases into the tubes, which stretches out within the tubes the arc formed between them until the arc is broken either in the tubes or at the fuse. It 80 is evident that the fuse is reliable in action, and since the arc is almost instantly extin-

guished no damage to the fuse structure is produced when the fusible strip is blown.

Fig. 2 shows a modification in which one tube is dispensed with and one fuse-contact terminal f' serves, with the movable tube C, to produce the second break in the circuit. The operation is the same as has been already described, and this modification requires no further explanation. Here the action is identical in principle with the design of Fig. 1, except that the stretching of the arc obtains only at one point. Although I have shown a fuse structure in which the pressure generated by the volatilization of the fuse metal acts directly upon a piston carried by the movable contact to produce the second break in the circuit, it is obvious that other equivalent arrangements may be employed. Other variations may be made in the construction and arrangement of parts, and I aim in the appended claims to cover all modifications which are within the scope of my invention.

What I claim as new, and desire to secure by Letters Patent of the United States, is—

1. In a cut-out for electric circuits, a chamber, a fuse contained therein, a movable member subjected to the pressure generated in said chamber when the fuse blows, a movable contact within said chamber operatively connected to said member, a stationary contact, and means for holding said movable contact normally in engagement with said stationary contact, said contacts being included in circuit with said fuse.
2. In a cut-out for electric circuits, a chamber, a fuse contained therein, a movable contact within said chamber in circuit with said fuse, and means responsive to a rise of pressure in said chamber for moving said contact.
3. In a cut-out for electric circuits, a chamber, a fuse contained therein, a movable contact within said chamber in circuit with said fuse, a movable member subjected to the pressure generated in said chamber when the fuse blows, and operative connections between said member and said contact.
4. In a cut-out for electric circuits, a chamber, a fuse contained therein, a movable contact in circuit with said fuse, and means responsive to a rise of pressure in said chamber for moving said contact, said contact being arranged when moved to open a passage from said chamber to atmosphere.
5. In a cut-out for electric circuits, a chamber, a fuse contained therein, a movable contact in circuit with said fuse, a movable member subjected to the pressure generated in said chamber when the fuse blows, and operative connections between said member and said contact, said contact being arranged when moved to open a passage from said chamber to atmosphere.
6. In a cut-out for electric circuits, a chamber,

a fuse contained therein, a movable member subjected to the pressure generated in said chamber when the fuse blows, a movable contact operatively connected to said member, a stationary contact, and means for holding said movable contact normally in engagement with said stationary contact, said contacts being arranged when separated to open a passage from said chamber to atmosphere.

7. In a cut-out for electric circuits, a chamber, a fuse contained therein, a movable member subjected to the pressure generated in said chamber when the fuse blows, and a movable tubular contact in circuit with said fuse and operatively connected to said member and adapted when moved to offer a passage from said chamber to atmosphere.

8. In a cut-out for electric circuits, a chamber, a fuse contained therein, a contact in circuit with said fuse, a tubular movable contact at one end open to atmosphere and at the other end normally closed by the companion contact, a movable member subjected to the pressure generated in said chamber when the fuse blows, and operative connections between said member and said movable contact.

9. In a cut-out for electric circuits, a chamber, a fuse contained therein, a stationary contact in circuit with said fuse, a tubular movable contact extending through said casting and open at its outer end to atmosphere, means for holding the inner end of said movable contact normally in engagement with said stationary contact, a movable member subjected to the pressure generated in said chamber when the fuse blows, and operative connections between said member and said movable contact.

10. In a cut-out for electric circuits, a chamber, a fuse contained therein, a tubular contact yieldingly mounted in said chamber and connected in series with said fuse, and means responsive to a rise of pressure in said chamber operatively connected to said tubular contact.

11. A fusible cut-out comprising a closed chamber, a plug-fuse adapted to be inserted and withdrawn from said chamber, and means responsive to a rise of pressure in said chamber for breaking the circuit in which said fuse is connected when inserted.

12. A fusible cut-out comprising a closed chamber, a plug-fuse adapted to be introduced and withdrawn from the chamber, a tubular electrode yieldingly mounted in said chamber adapted to be moved by the pressure generated in the chamber when the fuse blows and to provide a discharge-path for the gases, and connections for coupling the electrode and fuse in series when the fuse is inserted.

13. A fusible cut-out comprising a closed

chamber, a plug-fuse adapted to be inserted and withdrawn from said chamber, a tubular contact in circuit with said fuse when inserted and adapted when moved to offer a passage from said chamber to atmosphere, and means responsive to a rise of pressure within said chamber for moving said contact.

In witness whereof I have hereunto set my hand this 22d day of September, 1904.
